E. J. Bridge, of Troy, N. Y.
Letters Patent No. 914, Dated July 14, 1857.

The schedule referred to in these Letters Patent, and making part of the same.

To all whom it may concern:

Be it known that I, E. J. Bridge, of Troy
County of Rensselaer, State of New York, have invented or produced
a new and original design for a Parlor Stove called the Model,
and I do hereby declare that the following is a full, clear and exact
description of the same, reference being had to the annexed draw-
ing and letters of reference marked thereon forming part of this Specifica-
tion, in which the drawing is a perspective view of the Stove.

The description of the drawing is as follows; A. is the
foot with (4) a band terminating in scrolls, forming the border (1), a
leaf springing from bottom of foot (2) arcade finishing on corbels (3) inden-
ted moulding. B, the bottom or hearth with (1, 1, 1) a flat round moulding
with indentations forming out edge of bottom. (2, 2, 2) a bead moulding,
(3, 3) scalloped moulding running round the bottom. (4, 5) aperitire
mouldings forming the base of front ends & back. (6, 6) the base of but-
tiefs. (7, 8) ornament on hearth slide, (7, 7) scalloped moulding, (8) an oak
leaf. C, the front with (a, a,) mouldings forming bottom of front. (b) moral-
ding forming a band or string course. (c) panel with (d) the ornament
formed with (h, h), leaves terminating in scrolls. (f, f,) leaves reversed
springing from (h, h). (g) a leaf in five divisions springing from center
of (f, f). (k, k,) the arch forming head of panel divided into four cusps.
(e, e, e) hood moulding finishing on corbels. (f, f, f, f,) arcade of lancet point-
ed arches. (q_x, q_x, q_x) need moulding forming top of front plate. (h, h, h₂)
arcade ornament with corbels (i, i, i, i) under F, fire door. (j, j, j, j,) but-
tiefs forming corners. G, (e, sliding doors (a) the ornament (b, b,) leaves
terminating in scrolls. (c, c,) plain scrolls, (d) leaves springing from
scrolls (c, c.). (f, f, f,) arch of panel forming two cusps. (e, e,) Spandrels
ornamented with leaves. F, fire door (1) the ornament formed of (d, 2)

leaves springing from scrolls terminating in round heads (3.) leaf springing from center of ornament and overlapping parts of (2, 2.). (4, 4.) leaves springing from (2, 2.) finishing in scroll heads. (5) a corn forming finish of ornament. (6, 6, 6.) moulding forming border of door and finishing in ogee arch forming head of door. (7, 7.) arch of panel forming four cusps. H. ends or jambs (1) mouldings forming bottom of plate. (2, 2, 2.) tool mouldings. (3) need mouldings. (4, 4.) arcade terminating with corbels. (5) indented moulding. (6) ornament of panel. (7) leaf terminating in round heads. (8) leaf with scrolls. (9, 10.) same design as (8 & 9.). C. front. (11) arch forming head of panel, same design as (7, 7) F. fire door. (12) spandrels ornamented with oak leaves. (13) ornament filling head of arch, the center an oval figure with leaves radiating from it. D. top (ring) (1, 1.) bead moulding forming edge of ring.
